UNITED STATES PATENT OFFICE

GEORGE HOLZWORTH, OF HALIFAX, MASSACHUSETTS

DESIGN FOR A FLOWERPOT STAND OR SIMILAR ARTICLE

Application filed September 10, 1930. Serial No. 36,926. Term of patent 3½ years

To all whom it may concern:

Be it known that I, GEORGE HOLZWORTH, a citizen of the United States, residing at South Street, Halifax, in the county of Plymouth and State of Massachusetts, have invented a new, original, and ornamental Design for Flowerpot Stands or Similar Articles, of which the following is a specification, reference being had to the accompanying drawings, forming a part thereof.

Fig. 1 is a front elevation view of a stand showing my new design.

Fig. 2 is an edge view thereof.

I claim:

The ornamental design for a flowerpot stand or similar article as shown.

GEORGE HOLZWORTH.
